PERFORATORS

William H. Dreyer, Skokie, Ill., assignor to Cummins-Chicago Corp., Chicago, Ill., a corporation of Illinois
Filed Oct. 8, 1958, Ser. No. 766,044
3 Claims. (Cl. 83—290)

The invention relates to machines for perforating sheets of paper, cards and comparable sheet material and more particularly to an improved machine in which the perforating operation is carried out while the sheet or card is moving through the machine.

One object of the invention is to provide an improved perforating machine capable of operating at a substantially higher speed than perforators heretofore available and which is very smooth and quite in operation.

Another object is to provide a machine which perforates cleanly without bradding, burring or tearing the sheet material perforated.

A more specific object is to provide an improved rotary punch and die mechanism which is simple in construction, efficient in operation and particularly well adapted for high speed operation.

Still another object is to provide an improved die for perforating machines.

A further object is to provide a perforating machine which affords positive and accurate control over the location of the perforations.

Other objects and advantages of the invention will become apparent from the following detailed description of the preferred embodiment illustrated in the accompanying drawings in which—

FIGURE 1 is a fragmentary side view of a perforating machine embodying the features of the invention, portions of the housing being broken away to show internal details.

FIG. 2 is a fragmentary perspective view of a portion of the feed mechanism for the machine.

FIG. 3 is a fragmentary sectional view taken in a plane substantially on the line 3—3 of FIG. 2.

FIG. 4 is a fragmentary top view of the machine with the feed mechanism removed and portions of the frame and other parts broken away to show details.

FIG. 5 is a fragmentary sectional view through the punch and die mechanism of the machine on a somewhat enlarged scale.

FIG. 6 is a fragmentary sectional view of the punch and die elements on a still larger scale.

FIG. 6a is a fragmentary plan view of the die plate showing the plate arranged for perforating one type of indicia.

FIG. 7 is a sectional view taken in a plane substantially on the line 7—7 of FIG. 4.

FIG. 7a is a fragmentary sectional view through the clutch taken in a plane substantially on the line 7a—7a of FIG. 4.

FIG. 8 is a partially sectioned side view of the stop pawl mechanism.

FIG. 9 is a sectional view taken in a plane substantially on the line 9—9 of FIG. 4.

FIG. 10 is a fragmentary sectional view taken in offset planes substantially on the line 10—10 of FIG. 4.

FIG. 11 is a partially sectioned side view of the ink roll supporting structure.

FIG. 12 is a side elevational view of the trip switch assembly.

FIG. 13 is a simplified wiring diagram of the machine.

FIG. 14 is a fragmentary end view of the date stamp.

FIG. 15 is a top view of the dating unit.

While a preferred form of the machine has been shown by way of illustration, there is no intention to limit the invention to the particular form disclosed but the intention

2

is to cover all modifications and adaptations falling within the spirit and scope of the invention as more broadly or generally expressed in the appended claims.

General

For purposes of illustration, the invention has been shown as embodied in a machine for cancelling or otherwise marking bank checks, business machine cards and comparable documents by perforating suitable indicia therein. Perforation is effected by a punch and die mechanism 10 (FIGS. 4, 5 and 9) to which the documents are supplied in succession by a feed mechanism 11. Mechanism indicated generally at 12 is also provided for printing dates or other indicia on the documents simultaneously with the perforation. The various mechanisms are driven by an electric motor M which, along with suitable controls, is supported on a rigid frame structure 13. A housing 14 encloses the motor and other elements of the perforator except the feed mechanism 11, which is mounted for convenient access at the upper front end of the housing.

Perforating Mechanism

In accordance with one aspect of the invention the punch and die mechanism 10 is constructed and arranged in a novel manner to enable it to perforate documents in motion. More particularly, the perforation is effected while the documents are in course of transfer from a feed hopper 15 constituting a part of the feed mechanism to a receiving chamber 16 conveniently located in the housing 14. To this end, the punch and die mechanism 10 comprises a cylindrical punch carrier 20 and a cylindrical die carrier 21 supported for rotation on spaced parallel axes and driven in precisely timed relationship.

In the exemplary perforator the punch carrier 20 is fixed to a shaft 22 as by a pin 23 (FIG. 5). This shaft is journaled in antifriction bearings 24 having spring biased spacers 24' to preclude end play. In this instance, one bearing is provided on each side member of the frame 13 and a third is carried by a fore and aft upstanding web 25 constituting a part of the frame. The shaft is rotatably driven by the motor M through clutch mechanism 26 described hereinafter.

As shown in FIGS. 4 and 5, the die carrier 21 is mounted on a shaft 27 and secured to it by a pin 28. This shaft is likewise journaled in three antifriction bearings 29 having spring biased spacers 29'. The outer bearings are carried on the frame 13 and the central bearing is carried on a support post 30 suitably attached to the frame.

To insure synchronism in the rotation of the punch and die shafts and to avoid any misalignment due to wind-up of either shaft, the shafts are coupled together at both ends by intermeshing gears 31 and 32 fixed to the respective shafts. To provide for accurate timing and to eliminate backlash the gears are of composite construction. Thus, each gear 32 has an annular toothed ring, mounted adjacent and angularly adjustable relative to the toothed portion of the gear. Clamping screws 33' serve to lock the ring and gear in adjusted positions. The gear 31, as shown, comprises a toothed ring mounted on and adjustable angularly relative to a hub portion 34 which is keyed or otherwise nonrotatably fixed to the shaft. Clamping screws 35 extending through arcuate slots in the toothed portion of the gear permit limited relative adjustment of the parts and serve to clamp them securely in adjusted positions.

The punch carrier 20 is adapted to carry one or more sets of punches 40, each set being arranged to perforate a letter, numeral or any other desired symbol. For mounting the punches, the carrier is formed with appropriate groups of holes opening in its peripheral face and

extending into an annular channel 41 presented in one end face of the carrier. The pins are inserted in the holes and locked in place by filling the channel with a plastic material that becomes relatively hard or with solder or other low melting point metal as indicated at 42.

The die carrier 21 has a cylindrical body which carries an annular die plate 45 of steel or other suitable hard material. The die plate is formed with groups of punch receiving holes 46 suitably aligned for cooperation with the punches 40 and, of course, like the punches, grouped to form a desired symbol. It will be understood, of course, that the punches and the holes may be arranged in any desired pattern to provide the particular symbol required as, for example, the letters "PAID" as shown in FIG. 6a.

As shown in FIGS. 5 and 6, the carrier body is formed with a plurality of holes 47 aligned with the holes in the die plate for receiving the slugs 48 punched out by the punches in their passage through a document and the die plate. The holes 47 open into an annular chamber 49 formed in the die carrier which in turn opens in the face of the carrier to register with an annular chamber 50 formed in the bearing post 30. The latter chamber has an outlet 51 opening to a horizontal passage defined by a tube 52 (FIG. 4) for discharging the collected slugs into a receiving tray 53 or other suitable receptacle provided at one side of the housing 14. A pin 54 mounted on and rotatable with the carrier 21 projects into the chamber 50 to stir up the accumulated slugs and insure their movement into the outlet 51. To move the slugs along the tube 52, there is provided a feed screw 55, herein shown as comprising a helically coiled stiff wire. The feed screw is anchored at its outer end to a stub shaft 56 rotatably supported adjacent the outer end of the tube 52 and driven by a pinion 57 from the gearing coupling the shafts 22 and 27.

In accordance with one aspect of the invention, the punches 40 and die plate 45 are constructed in a novel manner which enables them to punch cleanly without bradding, embossing or tearing the sheet material. For this purpose, the holes 46 in the die plate are formed with a lip at their outer ends accurately dimensioned to receive the ends of the punches 40 with a sufficiently tight fit to produce a shearing action as the punches enter the holes. Inwardly of this lip the holes are enlarged as at 58 to insure passage of the punched slugs 48 into the holes 47 in the carrier. In the particular die plate shown, the dimensioned lips or punching portions of the holes 46 have a depth approximately one-half the diameter of the holes.

The punches 40, which may be constructed of the usual hardened punch wire, have their outer projecting ends formed to provide a sharp cutting edge 60, usually circular in contour. This cutting edge is backed by a narrow land 61 which is separated from the main body of the pin by a groove 62. Preferably the groove has one wall disposed substantially normally to the axis of the pin and the adjacent wall inclined at an angle to provide a relatively long tapered neck between the body of the pin and the land 61 adjacent the cutting edge.

The groove 62 formed in each punch 40 affords the relief required to permit the cutting edge of the punch to pass through the card being perforated and cut the material against the edge of the die hole with a clean shearing action without deforming the edges of the perforated hole in the rotation of the punch and die carriers. In other words, the construction referred to permits the punch cutting edge and die hole to be fitted precisely for clean cutting and yet affords clearance for the entry and exit of the punch elements through the holes in the card with the axes of the punches disposed at substantial angles to the card or sheet being perforated.

The punch and die carrier shafts 22 and 27 are rotated intermittently in timed relation to the presentation to the mechanism 10 of the sheet material to be perforated.

In the exemplary perforator the shafts and carriers mounted thereon are driven through one-half of a revolution in each operating cycle. Such intermittent or cyclic rotation is effected through the clutch mechanism 26 which may be of any suitable type. The improved clutch incorporated in the exemplary perforator and the associated controls are described in detail hereinafter. For present purposes, it is sufficient to note that the clutch mechanism includes a driving element 65 rotatably supported on the shaft 22 and a driven element 66 nonrotatably fixed to the shaft 22 adjacent one end of the driving element.

The driving element 65 is continuously driven in this instance by a pair of V-belts 67 from a pulley 68 journalled on a countershaft 69 supported on a subframe 70 suitably secured to the main frame 13. A pulley 71, which may be formed integral with or rigidly attached to the pulleys 68, is driven by a pair of V-belts 72 from a pulley 73 keyed or otherwise nonrotatably fixed to the shaft 74 of the motor M. This countershaft arrangement is provided for stepping down the speed of the driving clutch member with respect to the motor speed.

Engagement and disengagement of the clutch 26 is controlled by a stop pawl mechanism 75 to be described in detail later on. The pawl mechanism normally occupies a position effective to disengage the clutch. To engage the clutch the pawl is retracted in this instance by a solenoid SOL energized under control of a switch mechanism 76 actuated by the sheets to be perforated as they approach the perforating mechanism 10.

Feed Mechanism

While any suitable type of feed mechanism may be utilized for feeding sheet material to the punch mechanism, the feed mechanism 11 shown is generally similar to that disclosed in the Mentzer patent, No. 2,813,717, issued November 19, 1957. When the machine is to be employed for handling checks, business machine cards and similar sheets or documents of relatively small generally uniform dimensions, the feed hopper 15 is appropriately dimensioned to hold a stack of the sheets in vertical edgewise position. As shown in FIGS. 1, 2 and 9, the hopper 15 has a downwardly sloping platform 80 supported on the frame 13 with its lower end adjacent and slightly above the die carrier 21.

To provide for the accommodation of sheets of different length and to permit different selected areas of the sheets to be presented to the perforating mechanism, the hopper is equipped with adjustable side walls 81 and 82. The side walls, which may conveniently comprise stiff sheet metal members or plates, are supported for adjustment laterally of the hopper by a rod 83 extending transversely across the top of the machine and suitably mounted on brackets 84 upstanding from the machine frame. As shown in FIG. 2, each of the wall members is apertured to accommodate the rod 83 and aligned with each aperture is a sleeve 85 welded or otherwise rigidly secured to the wall member. The sleeves serve to hold the wall members upright while allowing them to slide axially of the rod 83. Thus, either or both of the wall members may be positioned transversely of the perforating mechanism to accommodate documents of a particular size and to accurately locate the area in which the indicia is to be punched.

As perforating machines of the character shown are frequently called on to handle large batches of sheets of one or more standardized sizes, provision is made for releasably retaining the wall members in selected positions conforming to the most frequently used sizes. While the retaining means may comprise clamping screws or the like if desired, I have shown the retaining means in the form of a yieldable detent (FIG. 3) in which a metal ball 86 slidable in a recess 87 in the sleeve 85 is yieldably urged against the rod 83 by a spring 88. The rod may be

formed with suitably spaced depressions or notches 89 for cooperation with the ball.

With the wall members 81 and 82 properly adjusted, a stack of sheets 90 placed in the hopper 15 as shown in FIG. 1 is held in place by a vertically disposed front plate 91 fixed to the hopper adjacent the lower end of the feed platform. A back plate 92 supported for movement forwardly and rearwardly by any suitable means such as a carriage 93 engages the rear of the stack and holds the sheets firmly against the front plate. In the exemplary machine, the carriage 93 is supported and guided by rollers 94 running on an inclined track 95 assembled with the feed platform. The carriage is urged forwardly by a spring 96 to compensate for the removal of successive sheets from the front of the stack.

Mounted forwardly of the front plate with its peripheral edge extending through an opening 97 in the plate is a feed roller 98 of rubber or other suitable material having circumferentially spaced projections or ribs 99. The feed roll is mounted on a shaft 100 extending transversely across the machine frame above and parallel to the shaft 27. Preferably the shaft is supported by brackets 98' suitably mounted on the machine frame. When the perforator is in operation, the feed roll shaft 100 is driven continuously from the driven clutch element. The drive, in this instance, includes a toothed pulley 101 (FIGS. 1 and 4) fixed to and rotatable with the driven clutch element 65. This pulley is connected by a notched belt 102 with a similarly notched pulley 103 rigidly secured to a transverse shaft 104 journaled on the machine frame. A pinion 105 on the shaft 104 drives an idler gear 106 journaled on the machine frame, which, in turn, drives a pinion 107 keyed to the feed roll shaft 100.

With the above arrangement the feed roll 98 rotates continuously to strip successive sheets 90 from the stack in the hopper and to feed them toward the punch and die mechanism. Each sheet, as it approaches the punch and die mechanism, initiates the engagement of the clutch 26 to drive the mechanism through a punching cycle. This is done through the medium of the switch mechanism 76 which is actuated by a trip lever 108 positioned for engagement by the sheet as it is fed from the hopper.

As shown in FIGS. 1, 10 and 12, the trip switch mechanism 76 is enclosed in a casing 109 supported on the machine frame forwardly of the shaft 104. Trip lever 108, herein shown as an elongated metal finger, is welded or otherwise fixed to and projects radially from a shaft 108' suitably journaled on the casing with the finger extending into the path of the sheet as it is advanced by the feed mechanism as shown in FIG. 10. A second arm or finger 109' fixed to the shaft 108' extends radially therefrom for coaction with the actuator 110' for the switch mechanism 76.

To effect movement of the sheets to the punch and die mechanism without slippage and to insure their presentation of the proper area to the punches, provision is made for positively advancing the sheets delivered by the feed roll 98. As herein shown, the sheets are carried through the perforating zone by a pair of feed belts 110 (FIGS. 5 and 10) running over pulleys 111 on the driven shaft 104 and pulleys 112 mounted on a shaft 113. The shaft 104 is suitably supported on the machine frame 13 above and substantially midway between the shafts 22 and 27. The shaft 113 is also supported on the frame 13 below and slightly to the right of the shaft 27 as viewed in FIG. 10. The positioning of the pulleys 111 and 112 is such that the intermediate portions of the belts 110 engage a substantial area of a pair of guide rolls 115 rotatably supported on the shaft 27 on opposite sides of the die roll 21 as shown in FIG. 5.

The belt supporting pulleys and guide rolls are spaced apart laterally so as to grip the sheets 90 at opposite sides of the punch and die mechanism and to advance them in a straight path for accurate location of the areas to be

perforated. To prevent deflection or bending of the sheets by engagement with the trip lever and to maintain the sheet flat during entry and withdrawal of the punches, a split finger or baffle 116 of nylon or other suitable material is positioned to press the sheets against the die roll on opposite sides of the punches and in the vicinity of the lever as shown in FIGS. 6 and 10. In the exemplary embodiment, the finger 116 is supported by a resilient metal bracket 117 mounted on the frame structure.

Movement of the sheets by the belts 110 is accurately timed with respect to the operation of the perforating mechanism since the belt driving shaft 104 and feed roll shaft 100 are driven by a common driving train from the driving member of the clutch 26 which drives the perforating mechanism. Idler pulleys 120 (FIG. 10) supported on brackets 121 pivoted on the shaft 113 engage the intermediate portions of the belts 110 to maintain them properly tensioned for feeding purposes.

Ironing Mechanism

The smooth even feed provided by the above mechanism coupled with the position punching by the mechanism 10 insures clean and accurate perforation of the sheets 90. To remove any slight bradding or embossing of the sheets incident to their perforation, each sheet is carried under an ironing roll 125 (FIG. 10) before it is discharged into the receiving hopper 16. The ironing roll presses the perforated area of the sheet firmly against a backup roll 126 on the shaft 113 and thus effectively smooths out any irregularities in the sheet.

As shown in FIG. 10, an ironing roll 125 is rotatably supported by a shaft 127 adjacent one end of a bracket 128 pivoted at 129 on a frame member 130 to swing toward and from the backup roll. A coiled compression spring 131 acting between the frame and the bracket urges the ironing roll firmly against the backup roll. By pressing the bracket 128 upwardly against the action of the spring 131, the ironing roll 125 may be brought into contact with the die plate 45 on the carrier 50 to burnish the plate and thereby remove any irregularities from the cutting edges of the die holes.

Inking Mechanism

To make the perforated indicia easily readable provision is made for applying a light coating of printing ink or comparable marking medium to the tips of the punches 40. Accordingly, as the punches pass through the sheets 90 a light application of ink is left around each hole to make it stand out for visual checking.

The inking means, in its preferred form as shown in FIGS. 1 and 11, comprises an ink reservoir forming structure having side members 132 supporting at their forward ends an ink applying roller 133. The reservoir structure 55 is supported on a flat transverse member 134 of the frame through the medium of a bracket having upstanding arms 135 spaced apart to fit between the extended ends of the side members 132 of the reservoir. Pins 136 project laterally from the arms 135 and engage in notches 60 137 in the side members to retain the reservoir in place. Tension springs 138 connected between the bracket and the ends of a cross bar 139 extending across the reservoir and engaging in notches 140 in the side members 132 urge the reservoir structure in a direction to press the ink roller 65 133 against the tips of the punches 40.

To regulate the pressure between the ink roller and the punches, the limit position of the roller is determined by an adjustable stop screw 141. As shown in FIG. 11, the screw is threaded through a laterally projecting lug 70 142 on one of the side members of the reservoir structure. The lower end of the stop screw engages the upper face of the supporting bracket and consequently determines the position in which the ink roller is held by the springs 138. A lock nut 143 threaded on the stop screw provides 75 for securely locking the parts in adjusted positions.

Perforator Drive

In accordance with another aspect of the invention the clutch 26 which drives the punch and die mechanism intermittently as above described, is constructed and arranged to provide smooth quiet operation with a minimum of shock incident to the sudden stopping of the rotating parts at the end of each cycle. The clutch is also designed with a particular view of providing dependable, trouble-free service over long periods of continuous use.

As previously described in a general way, the clutch 26 includes a driving element 65 and a driven element 66. The element 65 as shown in FIG. 4 comprises a cylindrical body 145 having peripheral grooves 146 in its outer surface for accommodation of the driving V-belt 67, there being two such grooves in the exemplary embodiment. At one end, the body 145 has an extension 147 of reduced diameter upon which the pulley 101 is nonrotatably fixed. A central bore 148 through the body of the extension provides for the reception of a pair of flanged bearing sleeves 149 by which the clutch element is rotatably supported on the shaft 22.

Fixed to the end of the clutch body 145 opposite the extension 147 is a cup-shaped housing 150. In the exemplary clutch the housing is seated in a recess in the face of the clutch body and is secured to it by screws 150'. The housing extends over and encloses a cam 151 keyed to the shaft 22 and secured against axial movement on the shaft by a set screw or the like. As will be seen by reference to FIGS. 4 and 7a of the drawings, the internal diameter of the housing is somewhat greater than the external diameter of the cam. The cam 151, which is generally cylindrical, has a series of uniformly spaced flattened faces 152 formed on its peripheral surface, there being five such faces in the exemplary clutch. The surfaces 152 are spaced from the inner wall of the housing so as to provide clearance for a series of rollers 153, each of which has a diameter slightly greater than the clearance between the outer face of the cam and the inner face of the housing. Accordingly, when unrestrained, the rollers tend to move along the surface when the housing is rotated and exert a wedging action on the cam effective to drivingly couple the housing and clutch element 65 to the cam and shaft 22.

To permit engagement or disengagement of the clutch at will, means is provided for releasably restraining the following movement of the rollers 153, thereby preventing them from effecting the driving engagement as before explained. The restraining means in its preferred form comprises a cage 155 in the form of a cylindrical body loosely mounted on the shaft 22 and having a series of axially projecting fingers 156 extending between the wedge rollers 153. A sleeve-like extension 157 of the cage projecting oppositely from the fingers carries a coiled torsion spring 158 anchored at one end to the cage and at the other end to a collar 159 rigidly secured to the shaft 22 as by a set screw 160. By appropriate location of the collar, a load is applied to the spring 158 tending to rock the cage in a direction to engage the clutch.

Provision is made for interrupting the rotation of the cage to disengage the clutch and stop the shaft 22. When the cage is thus stopped the spring 158 is tensioned to condition it for rocking the cage to clutch engaging position upon release. For this purpose, the cage is fitted with a stop ring 161 (FIGS. 4, 7a and 8) nonrotatably secured to the cage as by interengaging toothed and notched surfaces. As herein shown, the stop ring is secured in place on the cage by split retaining rings 162.

In the exemplary clutch, the stop ring 161 is fitted with two outwardly projecting teeth or stop dogs 163 preferably in the form of inserts of hard material such as tungsten carbide. The dogs are mounted so as to present diametrically aligned stop surfaces for alternate engagement with an abutment presented by a stop pawl 165 forming a part of the pawl mechanism 75. Thus, the

5 pawl when interposed in the path of either dog effectively interrupts the rotation of the stop ring and cage and retains the latter in a rest position against the torque exerted on the cage by the spring 158. The clutch 26 is therefore maintained disengaged.

10 While stop pawl mechanism of any preferred type may be employed, the mechanism 75 of the improved machine is constructed and arranged to minimize shock incident to interruption of the rotation of the shaft 22 and disengagement of the clutch 26. The mechanism which carries the pawl 165 is mounted so that the pawl can be swung into or out of the path described by the dogs 163 to intercept or release the cage as desired. As shown in FIG. 8, the pawl 165 is carried by a pivoted arm or lever 166 in the form of an elongated metal bar having a transverse hole at one end fitted with a bushing 167 by which it is pivotally supported on a shaft 168 suitably mounted on the machine frame. Extending axially through the bar is a stepped bore 169 slidably seating the pawl 165 herein shown as a headed pin. The pin projects from the small diameter section of the bore beyond the end of the bar and has its head slidable in the large diameter section of the bore. The pivot shaft 168 for the arm 166 is located so that in the retracted or stop position of the pawl mechanism, the projecting end of the pin 165 is disposed in the path of the dogs 163 and thus effective to intercept the dogs in the rotation of the clutch cage.

15 To absorb the shock incident to the sudden stopping of the rotating parts, pin 165 is resiliently urged to its intercepting position. For that purpose, the large diameter portion of the bore in the bar 166 is closed off by the bushing 167 and between the bushing and the head of the pin is interposed a resilient shock absorber. While the shock absorber may comprise a heavy compression spring if desired, it has been shown here as a pad 171 of rubber or other suitable material. Accordingly, when the end of the pin is engaged by the dog 163 to disengage the clutch, the shock absorber, in this instance, the pad 171, effectively absorbs the shock imposed on the pin.

20 The pawl 165 is normally held in clutch disengaging position by a spring 172 connected between an anchoring post 173 on the machine frame and a post 174 projecting laterally from the bar 166 as shown in FIG. 8. Withdrawal of the pawl to engage the clutch is effected by 25 the solenoid SOL. As shown in FIG. 7, the solenoid is mounted at one side of the pawl mechanism and its armature 175 is pivotally connected to a link 176 which in turn is pivotally connected to an extension of the bar 166. The extension is formed in this instance by a pair of side plates 177 disposed on opposite sides of the bar 166 and riveted or otherwise rigidly secured to it.

30 The improved perforator may utilize any suitable control circuit. The exemplary perforator has been shown equipped with a novel control circuit similar to that disclosed in the copending application of James L. Quinn, Serial No. 810,411, filed May 1, 1959, now Patent No. 3,074,525, assigned to the assignee of the present invention. Referring to FIG. 13 of the drawings, it will be observed that the switch mechanism 76 comprises a

35 switch having a movable member normally engaging a contact 178 and adapted to swing away from that contact and engage another contact 179 upon actuation by the switch lever 108. The movable switch member is connected to a capacitor 180 and, when engaged with the contact 178, it connects the capacitor 180 across the supply line conductors L1, L2 in series with a resistance 181, a rectifier 182 and a manually operable switch S. Line L1, L2 supply electric current to the perforator. Switch S, which is the main switch, is closed manually when the 40 perforator is placed in operation. It completes the operating circuit for the motor M as shown and the motor runs continuously when the switch is closed. Closure of switch S also completes a circuit through the switch contacts 173 by which the capacitor 180 receives a charge 45 of current.

Upon actuation of the movable switch member into engagement with the contact 179, the capacitor 180 is connected to discharge through the winding of the solenoid SOL which energizes momentarily to retract the pawl 165. Upon such retraction the clutch cage 155 is instantly rocked by the spring 158 to clutch engaging position and the dog 163 is shifted sufficiently to allow the pawl to return to clutch disengaging position without interfering with the operation of the clutch. The clutch is engaged to drive the shaft 22 and as the shaft completes a half-revolution constituting, in this instance, a full cycle, its rotation must be stopped instantly. Accordingly, at the end of this half-revolution, the pawl 165 intercepts the companion dog 163 to disengage the clutch and terminate the cycle.

The control system also includes means for shutting off the machine in case the card or other document gets out of step with the perforating mechanism as it is advanced by the feed mechanism. For this purpose, a second trip arm 211 (FIG. 10) is positioned for engagement by the edge of the document upon movement of the same through a predetermined distance. The arm 211 is fixed to a shaft 212 pivoted on the machine frame which has a second arm 213 engageable with the actuator 214 of a switch 215. As shown in FIG. 13, the switch 215 has a movable switch member 216 normally engaging a stationary contact 217. When the arm 211 is engaged by a card or the like, member 216 is shifted into engagement with a stationary contact 218.

In the control circuit shown, contact 217 is connected through a resistance 219 to the rectifier 182 in parallel with contact 178 of switch 26. Switch member 216 is connected to a capacitor 220 which is accordingly charged when the switch member is in its normal rest position. Movement of the switch member to its alternate position connects the capacitor to the movable member of a switch 221 operated by a timing cam 222. The movable member 223 of the switch is engageable alternately with a pair of stationary contacts 224 and 225. Contact 224 is connected to one terminal of a relay 226 which has its other terminal connected to line conductor L2. Contact 225 is connected to one terminal of a resistor 227 which has its terminal connected to line conductor L2.

The timing cam is mounted on and rotatable with the driven shaft 22. It is shaped and positioned on the shaft so that it swings the switch member 223 away from contact 224 and into engagement with contact 225 at the instant the card reaches the arm 213 when its movement is properly synchronized with the rotation of the punch and die members. Accordingly, when the card is in the correct position for perforating capacitor 220 is connected to dissipate its charge through the resistor 227 and the machine continues in its normal operating cycle.

If the card to be perforated is out of step with the punch and die mechanism, the condenser discharge circuit through contact 218 will be completed while switch member 223 is in engagement with contact 224. The condenser discharge will therefore energize relay 226 which, on energizing opens switch contact 228 to interrupt the current supply for the main driving motor M and other elements of the perforator. Relay 226 closes contacts 229 to complete a holding circuit for itself. Accordingly, the perforator stops and remains inoperative until the relay 226 is released by opening a manually operable reset switch 230, which, of course, is deferred until the out of step card has been removed from or properly positioned in the machine.

Brake Mechanism

Provision is made for preventing the shaft 22 from coasting and overrunning when the clutch 26 is disengaged as above described. For this purpose, the shaft is provided with an adjustable friction brake 185 as shown in FIGS. 4 and 9. The friction brake in its preferred form includes a drum 186 fixed to the shaft adjacent one

side of the machine frame. A pair of brake levers 187, each pivoted at one end on the frame 13, extend along opposite sides of the drum. Each lever carries an arcuate shoe 188 of suitable friction material engageable with the peripheral surface of the brake drum.

To maintain the frictional drag on the shaft 22, the brake levers are yieldably urged toward each other by suitable spring means. As shown, the free ends of the levers are apertured for the reception of a headed bolt 189. A washer 190 fitted on the bolt and abutting a nut 191 threaded thereon defines an abutment for a compression spring 192 which bears against the adjacent end of the lever, thus tending to swing the levers together and clamp them against the brake drum. By varying the position of the nut 191, the pressure exerted on the levers by the spring can be adjusted to provide precisely the required amount of friction on the brake drum for preventing shaft overrun.

Dating Unit

The dating unit 12 provided in the machine may be of any preferred construction. It is conveniently mounted at one side of the perforating mechanism in position to apply a line of printing and a date or other indicia on a document simultaneously with the perforation of the document as above described. As shown in FIG. 4, the unit includes a printing head 195 mounted on and rotatable with the shaft 22 carrying the punch unit. A platen roller 196 mounted on the shaft 27 and continuously driven by the belts 110 cooperates with the printing head for impressing printed matter on the card or document being perforated.

Referring to FIGS. 14 and 15, the printing head 195 as herein shown comprises a pair of generally Z-shaped side members 197 each having a central hub apertured to receive the shaft 22. The side members are preferably non-rotatably secured to the shaft as by set screws 199. Supported between the members 197 and securing them together as a unit are a pair of type clamping members 200 each comprising a pair of metal stampings fashioned to define a transverse slot 201 for receiving and retaining movable type slugs 202 of rubber, metal or other suitable material.

The two type slots are located on diametrically opposite sides of the shaft 22 to position them for printing in alternate cycles of the machine. Supported on the side members adjacent and parallel to the respective slots are a pair of printing bars 203 over which are trained a series of type bands 204. Each of the bands also extends around a band wheel 205 rotatably supported on a shaft 206 carried between the side members 197. One band wheel is provided for each type band, there being four in the exemplary machine. Preferably each of the band wheels is formed with a knurled rim 207 by which it can be turned manually to advance the associated band and selectively position the type on the outer face of the bar 203 for printing purposes. It will be observed that the outer corners of the bar 203 are rounded to facilitate easy sliding movement of the band over the bar.

The exemplary printing unit is shown as equipped with four of the bands 204. These are equipped with type for printing the month, day and year as shown in FIG. 15. It will be evident that any reasonable number of the type bands may be used and that they may be equipped with type for other than dating, as, for example, printing either numerals, letters or symbols as preferred.

Inking mechanism 210 is provided for inking the type of the printing head. The mechanism includes an ink roll 211 positioned to contact the type faces as the printing head rotates. While this inking mechanism may be of any suitable character, that shown is similar to the inking mechanism illustrated in FIG. 11 and previously described.

Operation

The operation of the improved perforator will be readi-

ly apparent from the foregoing detailed description. Briefly, a stack of the documents 90 to be perforated is placed in the hopper 15 with the foremost document abutting the front plate 91. The carriage 93 and associated back plate 92 are withdrawn for insertion of the documents and, upon release, the carriage advances with the front plate to press against the back of the stack, urging the entire stack in a forward position.

The machine is placed in operation by closure of the main switch S, thus starting the motor M which rotates the driven member 65 of the clutch 26. Through the drive train described, the feed mechanism is rotated continuously and the feed roll 93 strips the foremost document 90 from the stack and advances it to the feed belts 110. The feed belts in cooperation with the guide rolls 115 carry the document between the punch roll 20 and die roll 21 and discharge it into the hopper or receiving chamber 16. Immediately upon closure of the switch S a circuit is completed for charging the capacitor 180. As the first document approaches the perforating position it engages the trip arm 108 to actuate the switch mechanism 76. The switch mechanism interrupts the charging circuit for the capacitor and connects the latter across the winding of the solenoid SOL which becomes energized to retract the pawl mechanism 75. Retraction of the pawl mechanism withdraws the stop pawl 165 from engagement with stop dog 163, thus releasing the clutch cage 155 to the action of the spring 158 which rocks the cage in a direction to engage the clutch. Shaft 22 is accordingly driven to turn the punch and die members through a half-revolution in which the indicia set up on the punches is perforated in the document. As the back end of the document leaves the trip arm 108, the switch mechanism 76 is reactivated to close the charging circuit for the capacitor. Upon the advance of the next document the trip arm is again actuated and the cycle repeated.

Simultaneously with the perforation, the date and other printed matter set up on the printing unit 12 is impressed on the document. The location of the printed and perforated indicia laterally of the document is determined by the adjustment of the side members 81, 82 of the feed hopper. Vertical location of the indicia is determined by the position of the trip arm and the angular position of the printing head and punch carrier on the shaft 22.

Operation of the machine continues until all sheets in the stack have been run through the machine. This is accomplished very quickly as the sheets move continuously from the feed hopper to the receiving chamber 16, or, in other words, their travel is not interrupted during the perforating operation. This is made possible by the novel construction and arrangement of the punch and die elements which are constructed with a particular view of enabling the punches to enter the die holes at an angle and to retract therefrom at an angle as the punch and die holders are relatively rotated. Moreover, the punching is clean and sharp without embossing or bradding. Any small irregularities resulting from this operation are effectively removed by the ironing roll 125 before the document is deposited in the receiving chamber.

Slugs punched from the sheets or documents in the perforating process are removed from the perforating mechanism automatically and continuously and deposited in a tray conveniently accessible at one side of the machine frame. Accumulation of the slugs that might interfere with clean perforating is thus avoided.

It will be apparent from the foregoing that the invention provides a perforating machine of novel and advantageous construction. The machine is smooth and quiet in operation and capable of operating at substantially higher speeds than perforators as heretofore constructed. The arrangement for perforating without interrupting movement of the documents between the feed hopper and receiving chamber is an important factor in speeding up the output of the machine. The punching is clean and accurate with a minimum of bradding and substantially

no tearing of the sheet material. Any small irregularities are effectively removed before discharge of the perforated document.

I claim as my invention:

5 1. In a perforating machine for applying perforations to successive sheets of material, the combination comprising, a pair of cylindrical carriers supported for intermittent rotation about parallel spaced axes, means for driving said carriers intermittently, means engaged by each of said sheets for actuating said intermittent drive means in synchronism with passage of the successive sheets of material, a series of punch elements mounted on and projecting radially from one of said carriers, a cylindrical die plate mounted on the other of said carriers, said die plate having a series of holes positioned to receive the punch elements in the rotation of the carriers, and means for continuously feeding successive sheets of material between said carriers, said punch elements and said die plate in normally inoperative relation so that upon actuation of said intermittent drive means said punches and said die plate cooperate to punch holes in said sheets of material in their passage between the carriers.

2. In a perforating machine for applying perforations to successive sheets of material, the combination comprising, a pair of cylindrical carriers supported for intermittent rotation about parallel spaced axes, means for driving said carriers intermittently, means engaged by each of said sheets for actuating said intermittent drive means in synchronism with passage of the successive sheets of material, a series of punch elements mounted on and projecting radially from one of said carriers, a cylindrical die plate mounted on the other of said carriers, said die plate having a series of holes positioned to receive the punch elements in the rotation of the carriers, a pair of rolls supported for rotation about axes parallel to the rotational axes of said carriers, means for continuously feeding successive sheets of material between said carriers and between said rolls, said punch elements and said die plate in normally inoperative relation so that upon actuation of said intermittent drive means said punches and said die plate cooperate to punch holes in said sheets of material in their passage between the carriers, one of said pair of rolls being selectively movable into engagement with the other roll of the pair and alternatively into engagement with said die plate to sharpen the cutting edges of the plate, and spring means normally urging said one roll toward its companion roll with sufficient force to smooth out any irregularities in the sheet material resulting from the passing of the punches therethrough.

3. In a perforating machine for applying perforations to successive sheets of material, the combination comprising, a pair of shafts supported in parallel spaced relation, a pair of cylindrical carriers mounted on respective ones of said shafts for intermittent rotation about parallel spaced axes, means for driving said carriers intermittently, means engaged by each of said sheets for actuating said intermittent drive means in synchronism with passage of the successive sheets of material, a series of punch elements mounted on and projecting radially from one of said carriers, a cylindrical die plate mounted on the other of said carriers, said die plate having a series of holes positioned to receive the punch elements in the rotation of the carriers, means for feeding sheet material between said carriers for perforation by said punch elements and die plate, said sheet feeding means including a hopper operative to hold a stack of sheets to be perforated, a feed roll operative in its rotation for stripping successive sheets from the stack in said hopper and advancing the sheets toward said carriers, and feed belts operative to carry the sheets successively between said carriers, said intermittent drive means including a clutch having a driven element fixed to one of said shafts and a continuously rotating driving element rotatably mount-

ed on said one shaft adjacent said driven element, and means connecting said clutch driving element for continuously driving said feed roll and said feed belts, said punch elements and said die plate in normally inoperative relation so that upon actuation of said intermittent drive means said punches and said die plate cooperate to punch holes in said sheets of material in their passage between the carriers.
